UNITED STATES PATENT OFFICE.

ROBERT LEE BURNS, OF TAFT, CALIFORNIA, ASSIGNOR TO THE GUIBERSON CORPORATION, OF DALLAS, TEXAS, A CORPORATION OF TEXAS.

WELL-TUBING CATCHER.

Application filed May 23, 1921. Serial No. 471,622.

To all whom it may concern:

Be it known that I, ROBERT LEE BURNS, a citizen of the United States, residing at Taft, in the county of Kern and State of California, have invented a new and useful Well-Tubing Catcher, of which the following is a specification.

My invention relates to well-tubing catchers, and particularly to that type employing the automatic expansion of a weight compressed spring to propel a gripping member into operative position upon a fall of the well tubing. This application is substantially identical with that of my abandoned 15 application, Serial No. 324,174, filed September 16, 1919.

Automatic well-tubing catchers have found extensive favor in the art within recent years. These devices have depended for operation upon the automatic expansion of a weight compressed spring, which accompanies a fall of the device bearing the weighted spring. This automatic expansion has been utilized as a means for propelling 25 gripping members into wedging position between a well casing and the device carrying the gripping members. These prior devices have employed a weight independent of the gripping devices to effect the spring compression. My invention aims to eliminate 30 the necessity for an independent weight and to utilize the weight of the gripping devices as the means for effecting spring compression. To accomplish that end I have found 35 it necessary to provide an entirely novel combination of parts and employ constructions and principles not heretofore found in well-tubing catchers.

An object of my invention is to provide in 40 a well-tubing catcher of the type referred to, an arrangement of parts and elements wherein the weight of the gripping elements will serve as the means to effect spring compression.

45 A further object of my invention is to provide such a device which will be positive and sure in operation and susceptible in the least possible degree of derangement and disorder in use.

50 Another object of my invention is to provide such a device which will be practical and economical in manufacture.

55 Other objects and advantages will appear from the following description of a preferred embodiment of my invention.

Referring to the drawings:

Figure 1 is a vertical section of a well casing illustrating in elevation a well-tubing catcher embodying my invention positioned within a string of well tubing during normal operations.

Fig. 2 is a vertical section of the well casing and device of Fig. 1 illustrating the position assumed by the parts thereof upon a break or fall of the well tubing.

Fig. 3 is a horizontal section taken on a line indicated by x^3-x^3 in Fig. 1.

Fig. 4 is a horizontal section taken on line indicated by x^4-x^4 in Fig. 1.

In the drawings, 1 indicates a well casing 70 enclosing a well tubing having an upper section 2 and a lower section 3, a tubing catcher being interposed between said sections.

The tubing catcher includes a body 4 having an upper cone shaped portion 5 and a lower extension 6. The cone shaped portion 5 is provided with an annular shoulder 7 and a neck 8. The neck 8 is threaded for connection with the end of the well tube section 2. The cone section 5 has a central bore 9 registering with the bore of the well tubing. The lower extension 6 of the body 4 is provided with an annular shoulder 10 corresponding in diameter to the annular shoulder 7 on the cone portion 5. The extension 6 is threaded at its upper end within the cone portion 5 and is threaded at its lower end for connection with the end of the well-tube sections 3. The extension 6 has a central bore 11 registering with the bore 9 of the cone section 5 and with the bore of the well tubing. Although the body 4 is composed of the portions 5 and 6, when assembled, the same functions as an integral structure. The body 4 may be inserted between 95 two sections of a well tubing and will maintain unbroken the passage through the well tubing as illustrated.

A plurality of guide rods 12 extend from the annular shoulder 7 and are rigidly held 100 in spaced relation parallel to the conical surface of the body section 5. Gripping or wedging members 13 are slidably mounted upon the rods 12. The outer faces of the members 13 are serrated circumferentially 105 and in general parallel to the well-casing 1. The other side of each of the members 13 is smooth and conforms to the angular faces of the cone surface of the body 4. In the art these members 13 are denominated slips. 110

The cone shaped surface on the body 4 forms an expanding abutment for the slips. In normal use the slips 13 are positioned in contracted position along the expanding abutment. Upon a fall of the well tubing carrying the device the slips are propelled in a manner hereinafter described along the expanding abutment to the wedging position illustrated in Fig. 2.

10 Means are incorporated in the device for automatically propelling the slips 13 relative to the expanding abutment. A compression spring 14 is positioned between the annular shoulder 10 and each of the slips 13.

15 The slips 13 are each formed with a chamber 15 extending upward from their undersides. The compression springs 14 surround the guide rods 12 and bear at one end against the slips 13 within the chamber 15 and at the other end upon the annular shoulder 10. The weight of the slips 13 relative to the tension or expansion force of the springs 14 is such that the slips 13 normally maintain the springs under compression.

20 The lower outer edge 16 of the slips 13 is slanted or beveled off to coincide with a beveled lip 17 formed on the periphery of the annular shoulder 10. Normally the slip 13 will be seated on the lip 17 with the

25 springs 14 under compression as illustrated in Fig. 1, so that the springs while compressed by the slips do not constitute the sole support for the same. The weight of the slips 13 relative to the tension of the

30 springs 14 is great enough to cause the slips to seat as described, but is not so great as to deter the springs from automatically propelling the slips to expanded position as hereinafter described.

35 The slips 13 are connected together by pins or links 18, so that the slips will act in unison. In Fig. 4 the construction and assembly of the links 18 is illustrated in detail.

The tubing catcher is assembled on or within a string of well tubing and during normal operations the parts maintain the positions illustrated in Fig. 1. The well tubing may be raised or lowered under control without interference from the tubing catcher because the weight of the slips maintains the springs under compression and the slips remain out of engagement with the well casing. Upon a break or fall of the well tubing carrying the tubing catcher the compression within the springs 14 will be automatically released and the slips will pass along the conical abutment to the expanded position illustrated in Fig. 2. The fall of the well tubing will be thereupon checked by the wedging of the slips between the well casing and the conical abutment.

It should be noted that the weight of the slips is relied upon to compress the springs. In that respect my invention reduces the number of parts required in prior devices to

perform the same function. But to utilize the weight of the slips as the sole means for compressing the springs necessitates that the springs shall be relatively small and the device thus provided extremely sensitive. 70 Therefore it is necessary to provide particularly against derangement of the parts during normal operation of the well-tubing. The opposed annular shoulders 7 and 10 are effective for that purpose as they protect 75 the spring poised slips above and below from abnormal contact with anything within the well. The mounting of the springs within the chambers in the slips protects the same from being sanded up or otherwise fouled by extraneous material within the well, particularly as normally the spring chambers are in effect sealed by the seating of the slips on the shoulders 10. The fact that the slips are seated on the shoulders 10 insures that 80 the movement incident to the lowering or raising of the well-tubing on the vibration of the same during pumping will not cause the slips to shift to wedging position as might tend to occur if the slips were sensitively 85 mounted solely on the coiled springs.

As appears from the above I have provided a device of the character referred to embodying novel principles of action and improved expedients of construction. The 95 device is efficient and durable in action and economical and simple to manufacture. It may be positioned at any desired point on a string of well-tubing.

While I have illustrated a preferred embodiment of my invention incorporating various dependent and independent features, it is to be understood that my invention is not limited to the details of construction and relation of parts in such preferred 100 embodiment but is of the scope set forth in the following claims.

I claim:

1. A well tubing catcher comprising an expanding abutment, slips slidably mounted 110 on the abutment, and compression springs normally maintained under compression by the weight of the slips, the compression of the springs being automatically released upon a fall of the device to propel the slips 115 to expanded position.

2. A well tubing catcher comprising an expanding abutment, slips slidably mounted on the abutment and compression springs under the slips, the weight of the slips normally maintaining the springs under compression and the slips seated upon a shoulder below the abutment. 120

3. A well tubing catcher comprising a body including an expanding abutment, 125 spaced annular shoulders above and below said abutment, guide rods extending parallel to said expanding abutment intermediate said shoulders, and spring poised slips on said rods slidable along said abutment. 120

4. A well tubing catcher comprising a body including an expanding abutment, spaced annular shoulders above and below said abutment, guide rods extending intermediate said shoulders, slips slideable on said rods along said abutment, compression springs under said slips and seated on the lower of said shoulders, the weight of said slips maintaining said springs normally under compression.
5. A well tubing catcher comprising an expanding abutment, slips slidably mounted along the abutment, and compression springs seated upon a shoulder below said abutment, said springs extending within chambers formed in the underside of said slips and normally maintained under compression by the weight of said slips.
6. In a well tubing catcher a spring poised slip, the weight of the slip normally maintaining the spring under compression so that upon a fall the compression will be released to automatically expand the slip.
7. A well tubing catcher comprising a body including an expanding abutment, slips 25 slidably mounted on the abutment and compression springs under the slips, the weight of the slips normally maintaining the springs under compression, and links connecting the slips to cause the slips to move 30 in unison.
8. In a well tubing catcher a spring poised slip, the weight of the slip and the power of the spring being relatively proportioned so that normally the slip will compress the spring sufficiently to maintain the slip in retracted position and upon the tubing falling the spring will automatically propel the slip to expanded position.

Signed at Taft, California, this 12th day of May, 1921.

ROBERT LEE BURNS.
